UNITED STATES PATENT OFFICE.

VICTOR R. HEFTLER, OF DETROIT, MICHIGAN, ASSIGNOR TO SOCIETE DU CARBURETEUR ZENITH, OF LYON, FRANCE, A CORPORATION OF FRANCE.

CARBURETOR.

Application filed December 27, 1921. Serial No. 524,846.

Figure 1 is a longitudinal section on the line I—I of Figure 2; and

Figure 2 is a sectional view on the line II—II of Figure 1, looking in the direction of the arrows.

The present invention relates broadly to carburetors, and more particularly to carburetors of the type generally disclosed in Patent 1,562,806, granted to Richard H. Taylor, Nov. 24, 1925, having a low speed feeding device terminating at such position within the carbureting passage as to be effected by the position of the throttle.

In carburetors of this general type, it is not uncommon to feed the slow speed feeding device from a well open to the atmosphere in such manner that an emulsion is supplied by the slow speed feeding device to the carbureting passage. By the term "emulsion" as used herein, I mean a mixture of fuel and air in which the fuel is in more or less globular form and the air more or less in the form of bubbles. Such a construction makes it possible to provide an adjustment for the slow speed feeding device by varying the amount of air in the emulsion.

It has also been proposed, as disclosed, for example, in the application referred to, to provide a second well open to the atmosphere and fed from the first well in such manner that it receives fuel only when the engine supplied by the carburetor is at rest, the fuel therein being exhausted by an auxiliary fuel feed discharging into the carbureting passage independently of the slow speed feeding device, and effective only for starting. An important object of the present invention is to combine this auxiliary fuel feed with the slow speed feeding device in a novel and efficient manner.

The foregoing and other objects of the invention, together with their attendant advantages will be more clearly apparent as the invention becomes better understood, it being premised that changes may be made in the construction and operation without departing from the spirit of the invention or scope of my broader claims.

A carburetor embodying the present invention may comprise a constant level chamber 2 receiving fuel in any well known manner and delivering the same through a chan-

nel 3 to a main nozzle 4. This nozzle may discharge into a venturi shaped carbureting passage 5 controlled by a throttle 6, as is customary in the art.

The channel 3 is also adapted to supply fuel to a main well 7, which may have a screen covered opening 8 to the atmosphere. The fuel feed to this well may be through a calibrated plug 9 the effective opening of which may be varied at will by the needle valve 10. This valve preferably has a threaded engagement of relatively high pitch with some portion of the body of the carburetor, and is adapted to be operated from the dash board of the vehicle by any well known form of mechanism, not shown, whereby the fuel feed is under the control of the driver of the vehicle. This constitutes a valuable feature of the present invention, as will be more fully pointed out hereinafter.

Extending into the atmospheric well 7 is a tube, or quill, as it is termed in the art. This quill 11 has its lower end terminating below the fuel level and adjacent the plug 9, and its upper end delivering through a restricted orifice 12 to the passage 13. This passage has leading thereinto at an angle a second passage 14 which discharges into the carbureting passage 5 adjacent the throttle 6. With such a construction it will be apparent that with the throttle slightly opened there will be a flow of pure fuel through the quill 11 into the carbureting passage, this fuel being mixed with the air passing through the carbureting passage to form a combustible mixture.

Adjacent the atmospheric well 7 is a second well 15 having a suitable opening 16 to the atmosphere. The well 15 is supplied with fuel through an orifice 17 which is slightly below the normal level of the fuel in the constant level chamber and the highest level of the fuel in the atmospheric well 7. This construction is such that the well 15 will only be supplied with fuel when the level of the fuel in the atmospheric well 7 is very nearly equal to the level of the fuel in the constant level chamber. Extending into the well 15 and terminating adjacent the bottom thereof is a second quill 18 which discharges at its upper end into the passage 13. The flow through this second quill into

the passage 13 is regulated by an adjustable needle valve 19.

The well 7 also supplies fuel to the compensating fuel feed jet 20 in a well known manner, whereby with the carburetor supplying fuel in normal manner to the engine, the fuel level in the well 7 will be kept below the level of the fuel in the constant level chamber. The rapidity with which this lowering occurs will be partly determined by the position of the needle valve 10.

Assuming the engine to be at an absolute standstill, the fuel from the constant level chamber will reach the same level in all of the passages. As soon as the engine is started, the fuel level in the main atmospheric well 7 will drop due to the effect of the slow speed feeding device terminating adjacent the throttle. The orifice 17 is so positioned that it will be slightly above this new level assumed by the fuel in the main atmospheric well. When the engine is started, the throttle valve being kept in a nearly closed position, the high vacuum obtained will not only draw fuel from the well 7 through the slow speed feeding device as described, but will also draw pure fuel from the well 15 through the quill 18. This auxiliary fuel supply from the well 15 at this time is very helpful in starting.

Immediately after the engine has started and the first inrush has taken place, the engine will be working under suction and will maintain the level of the fuel in the atmospheric well 7 below the orifice 17. This will prevent the auxiliary well 15 from receiving any more fuel until the engine is again brought to rest. With the well 15 receiving no supply, it will be quickly emptied, and thereafter the quill 18 will supply nothing but air to the passage 13. The amount of air so supplied may be easily regulated by adjusting the needle valve 19.

The carbureting passage is preferably constructed of an upper section 21 of some inexpensive material which may be of a corrodible nature, and a lower section 22 which may be integral with the float chamber. The section 22 is preferably of more expensive material of a non-corrodible nature made necessary due both to the presence of acids and water in present day fuels. These sections, being separable, permit the assembly of the quills as well as the easy machining of the parts. The venturi per se may be composed of a cheap alloy die casting. These features of the present invention are described and claimed in my co-pending application Serial No. 531,647, filed January 25, 1922.

From the foregoing it will be apparent that the quill 7 never supplies anything but pure fuel, and that except for a brief intermediate period the quill 18 supplies either pure fuel or pure air. Both of these quills

deliver to a common passage communicating with the carbureting passage, thereby making it possible to provide at low speeds the small amount of mixture required.

By the provision of the needle valve 10, it will be possible to eliminate the usual choke, if desired, as this valve may be temporarily fully opened to cause a feed of rich fuel to the engine during the warming up period.

I claim:

1. A carburetor having a constant level chamber, a carbureting passage, a throttle valve in said passage, an atmospheric well, means to feed fuel to said well, a fuel feeding device communicating with said well and terminating adjacent the throttle, a second fuel feeding device from said well terminating below the throttle, a second atmospheric well communicating with the first atmospheric well below the normal fuel level of the fuel in the constant level chamber and above the fuel feed to the first mentioned atmospheric well, and an auxiliary suction fuel feed communicating with said second well at one end and said device at the other end to supply additional fuel to the carbureting passage at predetermined times, substantially as described.

2. A carburetor having a constant level chamber, a carbureting passage, a throttle valve in said passage, an atmospheric well, means for feeding fuel directly from the atmospheric well to an upper portion of the carbureting passage, means for feeding fuel from the atmospheric well to the lower portion of the carbureting passage, means for feeding fuel from the constant level chamber to the atmospheric well, a second well in communication with the upper portion of the atmospheric well, and an auxiliary feed for temporarily feeding additional fuel directly from the second well to said first mentioned fuel feeding means, substantially as described.

3. A carburetor having a constant level chamber, a carbureting passage, a throttle valve in said passage, an atmospheric well, means for feeding fuel directly from the atmospheric well to the carbureting passage below said throttle, means for feeding fuel from the constant level chamber to the atmospheric well, a second well in communication with the upper portion of the atmospheric well just below the normal level in the constant level chamber, and an auxiliary feed for temporarily feeding additional fuel directly from the second well to said first mentioned fuel feeding means, said first mentioned fuel feeding means being constructed to feed fuel only to the carbureting passage and said auxiliary fuel feed being adapted to first feed fuel only and then feed air only, substantially as described.

4. In a carburetor having a constant level

chamber, a carbureting passage, a throttle in said passage, a nozzle feeding fuel from the constant level chamber to said passage, a secondary nozzle terminating adjacent the of said fuel feeding means receiving its fuel from a source having a level fluctuation in excess of that in the constant level chamber, substantially as described. 10

5 throttle for delivering fuel to said passage, and a plurality of fuel feeding means delivering fuel to said secondary nozzle, one

In testimony whereof I have hereunto set my hand.

VICTOR R. HEFTLER.
